UNITED STATES PATENT OFFICE.

WILLIAM H. SCOTT, OF GOFFS, KANSAS.

WRENCH.

1,417,354.

Specification of Letters Patent. Patented May 23, 1922.

Application filed August 17, 1920. Serial No. 404,076.

To all whom it may concern:

Be it known that I, WILLIAM H. SCOTT, a citizen of the United States, residing at Goffs, in the county of Nemaha and State of 5 Kansas, have invented new and useful Improvements in Wrenches, of which the following is a specification.

The object of my present invention is the provision of a wrench, designed more particularly for automobile work and possessed 10 of a wide range of utility.

To the attainment of the foregoing the invention consists in the improvements as hereinafter described and definitely claimed.

15 In the accompanying drawings, hereby made a part hereof:—

Figure 1 is a view showing one use of which my novel wrench may be put.

Figure 2 is a section taken in the plane indicated by the line 2—2 of Figure 1, looking toward the left.

Figure 3 is a detail section taken at right angles to Figure 2 and in the plane indicated by the line 3—3 of Figure 1.

25 Figure 4 is a detail section taken on the line 4—4 of Figure 1.

Figure 5 comprises disconnected views of socket members of different types from those shown in Figure 1 and which may be used 30 interchangeably in the wrench. Any desired number of auxiliary socket members of different types may be provided for use interchangeably in the wrench to widen the range of usefulness thereof.

35 Figure 6 is a view showing the adaptability of a portion of the wrench to be used as a socket wrench.

Figure 7 is a view like Figure 6 but showing the wrench adapted for use as an efficient 40 screw driver.

45 Figures 8, 9 and 10 are detail views illustrative of the manner in which the T-head is detachably secured on the end of the shaft comprised in the wrench.

Figure 11 is a detail section on the line 11—11 of Figure 4.

Similar numerals of reference designate corresponding parts in all of the views of the drawings.

50 Among other elements my novel wrench comprises a frame. The said frame is made up of lapped bars 1 and 2. The bar 1 is provided at 3 with a transverse aperture, and is also provided at one end with an arm 4 that reaches at right angles therefrom and is provided with a circular aperture 5. The

other bar 2 is longitudinally slotted at 6, is provided at 7 with a loop that loosely receives the bar 1, and is provided at its opposite end with an angular arm 8 in which 60 is an aperture 9, of angular configuration, Figure 4, said aperture 9 being arranged in alinement with the before mentioned aperture 5. The bars 1 and 2 are adjustably connected through the medium of a headed and 65 threaded bolt 10, and a wing nut 11. Manifestly by virtue of this provision the lapped bars 1 and 2 may be adjustably fixed together to determine the distance between the arms 4 and 9 according to the work to be 70 done. In other words the frame may be increased or diminished in length as desired and then the lapped bars 1 and 2 may be adjustably fixed with respect to each other. It will also be noted in this connection that the 75 lapped bars reinforced and lend increased strength each to the other with the result that a strong and durable frame is produced.

In addition to the frame referred to, the wrench comprises a shaft 12, of circular 80 form in cross section, the ends 13 and 14 of which are of angular form in cross section. On the inner angular end 13 of the shaft 12 is removably arranged an interiorly angular portion of a socket member 15, and in 85 the angular aperture 9 is arranged the exteriorly angular portion of a socket member 16, Figures 4 and 11. At their inner opposed portions the said socket members are interiorly angular in order to engage the 90 head of a bolt and a nut on the bolt, respectively, after the manner shown in Figure 1. Being removable the socket members 15 and 16 are adapted to give place to socket members of different sizes and shapes of which 95 any desired number may be furnished in a kit.

Surrounding the shaft 12 and interposed between the abutment furnished by the enlargement of the end 13 and a washer 17 on 100 the shaft at the inner side of the arm 4 is a coiled spring 18, the function of which is to yieldingly thrust the shaft 12 toward the arm 8 of the bar 2.

The manner of using the wrench as thus 105 far described will be readily understood by reference to Figure 1, and need not therefore be enlarged upon.

The shaft 12 is equipped with a removable T-handle 19, said handle having an angular 110 aperture 20 to receive the angular end 14 of the shaft. It will also be noticed in this con-

nnection that in one side the said angular end 14 has a socket 21, and that the handle 19 is provided with a pin 22 adapted to enter the said socket 21 and thereby removably fasten the handle on the shaft. The pin 22 is movable through the aperture in one wall of the angular aperture 20 and is connected adjacent to its outer end to an intermediate point in a spring rod 23. Preferably the said rod 10 23 is extended through a diametrical aperture in the outer end of the pin 22, Figures 8, 9 and 10, and said spring rod 23 is arranged in a groove 24 in one edge of the handle 19 and is fixedly connected at one end of the 15 said handle 19 as indicated by 25. The opposite end of the spring rod 23 is provided with an arm 26. This arm extends loosely through a bore 27 in the handle 19 and is designed to rest at its free end in a recess 28 formed in the edge of the handle opposite to the edge at which the rod 23 is disposed. Manifestly by pressing with a thumb on the free end of the arm 26 the operator is enabled to move the pin 22 out of the socket 21 in the 25 handle end 14, whereupon the handle 19 may be slipped off the end 14 of the shaft 12. It also follows that the handle 19 may be expeditiously applied to and detachably fastened on the end 14 of the shaft 12. In Figure 6 I illustrate the manner in which the shaft 12, the T-handle 19 and one of the 30 socket members 15 or 16 may be used to form a socket wrench, and in Figure 7 I show that the said elements plus a screw engaging member 30 may be used to form an efficient screw driver.

The angular end 13 of the shaft 12, and the angular aperture 9 in the angular arm 8 are so constructed that any standard socket 40 member can be used in connection with the improved wrench.

It will be apparent from the foregoing that my novel wrench is especially adapted for removing the bolts from automobile 45 housings and differential casings, inasmuch as the wrench enables a single workman to do the work without the help of an assistant or assistants.

Having described my invention, what I

claim and desire to secure by Letters-Pat- 50 ent, is:—

1. A wrench comprising a frame made up of lapped bars one of which is provided with a transverse aperture and the other of which is provided with a longitudinal slot, and one 55 of which has a loop receiving the other and both of which have angularly-disposed arms spaced apart in parallel relation and in one of which is a circular aperture and in the other of which is an angular aperture alined 60 with the circular aperture, a headed and threaded bolt extending through the slot and aperture of the lapped bars, and a nut mounted on said bolt; a shaft of circular 65 form in cross section arranged in the circular aperture of one arm of the frame and having an exteriorly-angular inner end, a spring surrounding the shaft and interposed between said exteriorly-angular end thereof and one of the frame arms, a handle detachably fastened on the outer end of the shaft, and socket members, one removably arranged in the angular aperture of the frame and the other removably arranged on the exteriorly-angular end of the shaft, said 70 wrench capable of disassembly for convenient carriage in a tool box.

2. The combination with a shaft having an angular end and a socket in one side of said end; a handle having an angular aperture receiving the angular end of the shaft and also having a longitudinal groove in one of its edges and a bore extending from one end of said groove to the opposite edge of the handle and further having in said opposite 85 edge and in communication with the bore a recess, a pin movable through an aperture in one wall of the angular aperture in the handle and adapted to enter the socket in the shaft, and a spring rod connected at one 90 end to the handle in the groove thereof and extending through an aperture in the pin and having at its free end an arm extending through the bore in the handle to the recess in the opposite edge of the handle. 95

In testimony whereof I affix my signature.

WILLIAM H. SCOTT.
